UNITED STATES PATENT OFFICE

90,752

DESIGN FOR A GAME BOARD

William L. Deming, Salem, Ohio

Application December 30, 1932. Serial No. 46,665

Term of patent 14 years

To all whom it may concern:

Be it known that I, WILLIAM L. DEMING, a citizen of the United States, residing at Salem, in the county of Columbiana and State of Ohio, have invented a new, original, and ornamental Design for a Game Board, of which the following is a specification, reference being had to the accompanying drawing, forming part thereof.

I claim:

The ornamental design for a game board, as shown.

WILLIAM L. DEMING.
